ROLLER SHADE BRACKET

Filed March 13, 1925

INVENTOR
WILLIAM C. SMITH

Clayton M. Ross, Atty.

UNITED STATES PATENT OFFICE.

WILLIAM C. SMITH, OF CHICAGO, ILLINOIS.

ROLLER-SHADE BRACKET.

Application filed March 13, 1925. Serial No. 15,222.

The present invention has to do with a bracket or support for a roller shade, and relates to the particular construction and design of such members.

5 Among the objects of the invention are included the following:—

The provision of novel members of the character described adapted to hold the ends of a shade roller and possessing an adaptability for use in spaces of most limited dimensions such, for example, as car windows.

10 Brackets of the character described which facilitate the positioning of a shade roller and permit of the adjustment of the various elements thereof in less time than has heretofore been possible; and

15 The combination of a guide and supporting means facilitating the adjustment and setting of a shade roller in juxtaposition to a car window, such means including a novel structural form.

20 These, and such other objects as may hereinafter appear, are obtained by the novel construction, combination, and arrangement 25 of the several parts of the bracket members which constitute the invention, and by their association with the adjacent parts of the window construction.

25 One embodiment of the invention is illustrated, and in the drawing:—

Figure 1 is an elevation showing right and left hand brackets in position, the middle portion of the window, the window stop and the curtain moulding being removed;

30 Figure 2 is a vertical section on the line 2—2 of Figure 1;

Figure 3 is a front elevation, partly in section, similar to Figure 1 with the shade roller in lowermost position;

35 Figure 4 is a fragmentary side elevation of a left hand bracket;

Figure 5 is a similar view of a right hand bracket showing a shade and roller in lowermost position;

40 Figure 6 is a similar view with a shade roller in its operable position.

Like reference characters are used to designate similar parts in the drawing and in the description which follows:

45 For the purpose of suspending a spring actuated shade roller, brackets are ordinarily employed. A number of these have been proposed. In car construction, the space within which the shade rollers may be placed is quite cramped, first, because of the neces-

sity for conserving space, second, because the shade should be protected from removal by the travelling public by being made difficultly separable from the car structure, and third, because the bracket structure should 60 fall within the confines of the window frame.

In designing the space for the disposition of roller shades used in car construction, it has been customary to provide an enclosing member or moulding in order that a layman 65 ordinarily could not loosen the shade or remove it from its supports, or brackets.

In so doing, difficulty in "setting" the shade has been increased until at the present time a skilled workman requires from ten 70 to thirty minutes for hanging a single shade and adjusting the spring, therein to proper tension.

In the current invention, none of the compactness heretofore required and obtained 75 has been lost. The shade is no more readily removed by the unskilled than those previously difficultly hung, but the hanging of the shade is facilitated to the extent that it may be placed in position and all adjustments 80 of the spring required obtained in one or two minutes.

As indicated hereinbefore, shade brackets are right hand and left hand. One right hand and one left hand bracket are required 85 for each roller. The description of a bracket of one type except as to specific details will apply to a bracket of the other type, the parts being reversed.

90 A left hand bracket will be described first. Such a bracket is shown in Figures 1, 3, and 4. Each bracket comprises a blank of sheet metal generally indicated 10. At the top of the bracket 10 is a slight bend in the material to provide offset section 11 having a laterally extending top flange 12 adapted to be secured to the metallic lintel 13 by a screw 14 passing upwardly through the under side of said lintel 13 and said flange 12.

95 A similar offset section 15 substantially parallel to section 11 is provided at the bottom of blank 10 by a similar articulation thereof and is apertured to provide a screw hole for securing the bracket to the inner 100 wall of the window side frame generally called the window post, designated 16. That portion of the blank 10 between the sections 11 and 15 is therefore offset from window post 16 to provide additional end space for 110

the non-rotatable end of the shade roller which end projects into and through the slot in the blank 10 shortly to be described.

Upon the window side of the blank 10 are two flanges, 17 and 18, the upper 17 being adapted to be secured to the face of post 16 in any suitable manner, while the lower one 18 is of a fold of material arranged parallel to and in alignment with the lower section of lintel 13. Intermediate the flanges 17 and 18 is a cut-out section 19 which is adapted to receive the crimped, turned over or beaded edge of the lintel 13, it being usual to reinforce and protect such edge in one of these manners.

A section of material 20 converging as it extends away from the blank 10 is arranged upon inner and uppermost margin of blank 10, integral therewith, and the extremity of section 20 is bent inwardly to provide engagement with a moulding 21, previously mentioned. An upper flange 22 upon moulding 21 is secured to the face of lintel 13. Such moulding or housing 21 extends over the bracket 10 (and the right hand bracket 10^a) and is adapted to engage at its lower edge just beneath section 20 the material of the window post 16. Moulding 21 is generally placed in position and firmly anchored after the brackets have been positioned and before the shade roller is hung or adjusted to proper tension.

In bracket 10 is a slot 25. The lower end 26 of said slot 25 is enlarged to give it a substantially circular or truly circular configuration. Extending upwardly from said enlarged portion 26 the slot 25 is truly vertical or nearly vertical for a short distance and then is curved upwardly and outwardly, terminating in a downwardly extending substantially vertical portion 27. Intermediate the two slot sections 25 and 27 is a pointed portion 28 of the material of blank 10. The longer section 25 adjacent the pointed end 28 of section 28 is enlarged or widened and the distance between the projection 28 and the opposite wall of slot 25 may be sufficiently augmented to permit the non-rotating end of the shade roller to be turned over therein.

Right hand bracket 10^a corresponds to bracket 10 in that parts 11^a, 12^a, 15^a, 17^a, 18^a, 19^a, and 20^a correspond to parts 11, 12, 15, 17, 18, 19 and 20 on bracket 10. The slot construction is different for it is intended to receive the rotatable end of the shade roller. Slots 25^a and 27^a are of the same width throughout. At the bottom of slot 25^a is an inwardly dished section 26^a and a similar dished section 29 is provided at the lower end of slot 27^a. The rounded end of the shade roller is disposed against seats 26^a and 29 according to whether the shade roller is being adjusted or operably disposed.

The brackets 10 and 10^a are placed in po-

sition upon the lintel 13 and window post 16 in the manner indicated. A shade roller 30 is hung with its projecting end bearings in the slots 25 and 25^a and rests in the lower ends of such slots. Shade rollers comprise two telescoping sections, one of said sections 31 having movably disposed therein the squared or oblong lug 32 which is connected to the roller coil spring within section 31 as is usual in the shade roller art. Adjustments of lug 32 are latched by a dog 33 actuated by gravity. The other section 35 of the roller has the ordinary round axle or bearing 36. Intermediate the sections 31 and 35 is a locking member 37.

A crank or other member is used to rotate the spring in the roller 30. This is done outside the housing 21. The adjustment should only be enough to hold curtain 38 taut. The curtain fittings which ride in a vertical track in curtain moulding 38^a hold the curtain in any adjusted position. Adjustments may be made after the roller 30 is placed and with the dog 33 up as shown in Figure 5, but in operably seating a curtain so adjusted, the position of dog 33 should be changed to that shown in Figure 6 by turning the curtain over. A stop 39 is provided upon bracket 10 to register with the fittings on shade 38 and to prevent the shade 38 from being forced too high.

The inaccessibility to the shade in the old type of roller shade mountings has caused the invention. A single position for the roller well obscured by window moulding 21 made removal, repositioning and adjustment of shade rollers a difficult task. The provision of a guide providing several seats for a roller is novel. It is therefore my intention to claim this seat wherever found—in a bracket as described, or in the lintel, post or moulding.

I claim:—

1. As a new article of manufacture, a support for a window shade roller having one end to be held rigid during use comprising spaced brackets having an enclosed slot of two sections of different lengths joined at their top extremities, the section of less length in an inwardly hung bracket being further away from the window, the slot in one of said brackets being substantially the same width throughout, the slot in the other of said brackets having an enlarged portion at the lower end of the longer section to permit of free rotation of the shade roller without disturbing the tension of the spring therein.

2. As a new article of manufacture, a bracket for supporting that end of a roller shade housing a spring, and a dog for locking the roller and spring in selected position, a bracket comprising a blank of sheet material having a blind slot therein, said slot having an enlarged portion permitting

of free rotation of the shade roller and a narrow portion extending upwardly and outwardly therefrom and terminating in a vertical downwardly extending slot seating said roller in operable position and preventing rotation of said roller without change in the tension of the spring therein.

3. As a new article of manufacture, a bracket for holding roller window shades comprising a slotted member adapted to enclose the spring actuated end of the shade roller and formed from sheet material, the slot in said member having an enlarged portion from which a narrow section extends upwardly and forwardly to terminate in a shorter downwardly extending roller seating section, the junction between the two sections of the slot admitting of the roller being

turned to facilitate its hanging, said member having marginal extension portions for securing it concurrently to the lintel, window stop and moulding of a car, the portion adapted to be secured to said moulding containing said shorter section of said slot.

4. A curtain roller bracket adapted to be disposed in the back portion of a housing having an inwardly and upwardly extending wall and comprising an enclosed slot extending from beneath said housing upwardly and adapted to guide a curtain roller to and from its operating position, said slot having a substantially straight vertical section effective to receive a roller in an accessible position for guidance to an inaccessible operative position.

WILLIAM C. SMITH.
